UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR DIMINISHING THE RECOIL OF GUN-CARRIAGES.

1,310,141.

Specification of Letters Patent.

Patented July 15, 1919.

Application filed February 14, 1918. Serial No. 217,186.

To all whom it may concern:

Be it known that I, EUGÈNE SCHNEIDER, a citizen of the French Republic, and a resident of 42 Rue d'Anjou, Paris, France, 5 have invented new and useful Improvements in Apparatus for Diminishing the Recoil of Gun-Carriages, which invention is fully set forth in the following specification.

This invention has for its object to provide 10 an improved apparatus for diminishing the recoil of guns.

The improved apparatus is more particularly designed for use with gun carriage trucks designed to enable their guns to be 15 fired from a railroad track.

The improved apparatus when so used, serves for diminishing the recoil of the gun carriage truck along the railroad track, and for returning the gun automatically into position 20 for firing after the devices for transmitting the firing strains to the railroad track have been raised off the latter.

An embodiment of this invention is illustrated by way of example in the accompanying 25 drawings in which:—

Figure 1 is an elevation of a gun carriage truck designed to enable its gun to be fired from a railroad track and showing in vertical longitudinal section an embodiment of 30 the improved apparatus used in connection with said truck.

Fig. 2 is a plan of Fig. 1, partly in horizontal section on the line II—II of Fig. 1.

Fig. 3 is a vertical cross section drawn to 35 a larger scale on the line III—III of Fig. 1.

According to this invention the gun carriage truck which may be constructed in any desired manner is in each case provided with a series of retractable members E carried 40 permanently by the gun carriage truck A. These members E are adapted to move relatively to the gun carriage truck in such a manner as to be capable of being brought into contact with the railroad track when 45 the gun is being fired, for the purpose of transmitting the firing strains to said track. These members E are adapted to be raised rapidly out of contact with the railroad track for the purpose of returning the gun 50 into position for firing.

According to the present invention a brake and a recuperator of any suitable known construction, for instance of the hydro-pneumatic type, are formed in a box B pref-

erably mounted by means of vertical trunnions B¹ on a suitable support here shown as a casing C. This casing C is constructed in such a manner as to be capable of being placed upon and fixed to the rails M of the sliding track which may be a railroad track of standard gage or a field railway. The casing C is located in front of the gun carriage truck. The fixing of the casing C may be effected for instance by means of jaws K movable on axle pins k carried by the said casing. These jaws K can be moved into position to clamp the rails M by means of wedges L¹ operated by means of screws L working in corresponding screw-threads formed in the casing C. 70

In the example shown, the improved apparatus for reducing the recoil and for returning the gun automatically into firing position, comprises two brake cylinders D, D, located one on each side of a cylinder H 75 wherein the piston F of the recuperator works. This cylinder H communicates with two air chambers H¹, H².

The piston rods of the recuperator F and of the two brake pistons G are connected to 80 the gun carriage truck girder A in such a manner as to allow of the said truck recoiling along a portion of the track which may not be straight or horizontal.

For this purpose the means of connection 85 comprises a connecting member I to which are fixed the rods of the pistons F and G. This connecting member I is jointed on an axle pin J constituting one of the ends of a traction bar N. The other end of this traction bar is connected by a ball and socket joint O to the gun truck girder A. 90

For firing, the supporting members E are brought into contact with the railroad rails M. The recoil is braked by the brakes D. 95

After the recoil, the members E are moved quickly out of contact with the rails M.

The returning of the gun into firing position is then effected automatically by the action of the recuperator H. 100

The casing C containing the whole of the brakes and the recuperator, may be provided with rollers P such as are shown in the left hand portion of Fig. 3. These rollers will allow the casing connected to the bar N to roll through small distances necessitated by small shifting of the gun carriage truck. 105

For transport, the bar N is disconnected and the parts N—I—C are packed upon one of the trucks *a*.

What I claim is:—

- 5 1. In combination with a gun carriage truck designed to enable the gun to be fired from a railroad track, an apparatus for diminishing the recoil and returning the gun automatically into position for firing, comprising a support located in front of the gun carriage truck but separate from same, a brake and a recuperator located on said support, means for securing said support on the railroad track, and a pivotal connection connecting the movable elements of said brake and said recuperator to the gun carriage truck.
- 10 2. In combination with a gun carriage truck designed to enable the gun to be fired from a railroad track, an apparatus for diminishing the recoil and returning the gun automatically into position for firing, comprising a support located in front of the gun carriage truck but separate from same, a brake and a recuperator located in said box, means for securing said casing to the railroad track, a universal joint on the gun carriage truck, a pull bar engaging at one end with said universal joint and connected at the other end through a vertical pivot pin with said casing, for connecting the movable elements of said brake and said recuperator to the gun carriage truck.
- 15 3. In combination with a gun carriage truck designed to enable the gun to be fired from a railroad track, an apparatus for diminishing the recoil and returning the gun automatically into position for firing, comprising a support located in front of the gun carriage truck but separate from same, a brake and a recuperator mounted to turn on a vertical axis on said support, means for securing said support to the railroad track, and a pivotal connection connecting the movable elements of said brake and said recuperator to the gun carriage truck.
- 20 4. In combination with a gun carriage truck designed to enable the gun to be fired from a railroad track, an apparatus for diminishing the recoil and returning the gun automatically into position for firing, comprising a casing located in front of the gun carriage truck but separate from same, a box pivoted by means of vertical top and bottom trunnions in said casing, a brake and a recuperator located in said box, means for securing said casing to the railroad track, a universal joint on the gun carriage truck, a pull bar engaging at one end with said universal joint and connected at the other end through a vertical pivot pin with said casing, for connecting the movable elements of said brake and said recuperator to the gun carriage truck.
- 25 5. In combination with a gun carriage truck designed to enable the gun to be fired from a railroad track, an apparatus for diminishing the recoil and returning the gun automatically into position for firing, comprising a support located in front of the gun carriage truck but separate from same, a brake and a recuperator located on said support, means for securing said support on the railroad track, and a pivotal connection connecting the movable elements of said brake and said recuperator to the gun carriage truck.
- 30 6. In combination with a gun carriage truck designed to enable the gun to be fired from a railroad track, an apparatus for diminishing the recoil and returning the gun automatically into position for firing, comprising a support located in front of the gun carriage truck but separate from same, a brake and a recuperator located in said box, means for securing said casing to the railroad track, a universal joint on the gun carriage truck, a pull bar engaging at one end with said universal joint and connected at the other end through a vertical pivot pin with said casing, for connecting the movable elements of said brake and said recuperator to the gun carriage truck.
- 35 7. In combination with a gun carriage truck designed to enable the gun to be fired from a railroad track, an apparatus for diminishing the recoil and returning the gun automatically into position for firing, comprising a support located in front of the gun carriage truck but separate from same, a brake and a recuperator mounted to turn on a vertical axis on said support, means for securing said support to the railroad track, and a pivotal connection connecting the movable elements of said brake and said recuperator to the gun carriage truck.

prising a support located in front of the gun carriage truck but separate from same, a brake and a recuperator located on said support, means securing said support to the railroad track, a pull bar, and flexible connections between said pull bar and the gun carriage truck at one end and said support at the other end, for connecting the movable elements of said brake and said recuperator to the said gun carriage truck.

4. In combination with a gun carriage truck designed to enable the gun to be fired from a railroad track, an apparatus for diminishing the recoil and returning the gun automatically into position for firing, comprising a casing located in front of the gun carriage truck but separate from same, a box pivoted by means of vertical top and bottom trunnions in said casing, a brake and a recuperator located in said box, means for securing said casing to the railroad track, a universal joint on the gun carriage truck, a pull bar engaging at one end with said universal joint and connected at the other end through a vertical pivot pin with said casing, for connecting the movable elements of said brake and said recuperator to the gun carriage truck.

In testimony whereof I have signed this specification.

EUGÈNE SCHNEIDER.
